PITCHER

Raymond F. Daniel, Champaign, Ill.

Application March 27, 1939, Serial No. 264,455

1 Claim. (Cl. 65—31)

This invention appertains to new and useful improvements in pitchers such as cream pitchers.

The principal object of the present invention is to provide a cream pitcher which is constructed

5 in such a manner as to catch drippings from the pouring lip thereof.

This and other objects of the invention will become apparent to the reader of the following specification.

10 In the drawing—

Figure 1 represents a side elevational view with a portion in section.

Figure 2 is a front elevation.

Referring to the drawing, wherein like numerals designate like parts, it can be seen that the pitcher as constructed consists of the bottom 5 and the side wall A which consists of the upwardly flaring portion 6 merging with the upwardly converging portion 7. The front side of the pitcher

20 has the backwardly formed wall 8 which extends downwardly from the lip 9 and terminates at the point 10 which also forms the bottom of the pocket defined by the lower portion of the front wall 8 and the outwardly inclined wall 11 which is substantially flush with the lower portion 6 of the wall A. A short upwardly extending portion 12 is provided for the wall 11, and this portion 12 is disposed inwardly as at 13.

The depressed wall 8 converges upwardly merging with the narrow upwardly tapering channel-way 14 which terminates in the under side of the lip 9.

Thus it can be seen that after cream or other liquid has been poured from the pitcher, any drops remaining on the lip which have a tendency to fall off will run down the channel-way 14 and drop into the pocket 15. Thus the milk is caught and prevented from falling onto and soiling table-cloths 10 and other surfaces.

While the foregoing specification sets forth the invention in specific terms, it is to be understood that numerous changes in the shape, size and materials may be resorted to without departing 15 from the spirit and scope of the invention as claimed hereinafter.

Having described the invention, what is claimed as new is:

In a pitcher construction comprising a container wall, a lip at the upper portion of the wall, a pocket provided at the outside of the wall and underlying the lip, said wall being indented at its portion opposed to the pocket, said indented portion extending upwardly and gradually tapering to terminate at the overflowing edge of the said lip at the underside thereof. 20 25
